UNITED STATES PATENT OFFICE

WILLIAM B. PETZ, OF PLYMOUTH, MICHIGAN

SWIMMING TUBE

Application filed April 20, 1929. Serial No. 356,729.

The present invention relates to a rubber swimming tube which also may be used as a life preserver and has for its prime object to provide a device of this nature which may 5 be formed from one or more tubes constructed with a flat like portion to extend under the arms and air receiving chambers or reservoirs with inflation valves associated therewith.

10 Another very important object of the invention resides in the provision of a device of this nature which is exceedingly simple in its construction, inexpensive to manufacture, durable, thoroughly efficient and reliable in 15 use and otherwise well adapted to the purpose for which it is designed.

With the above and numerous other objects in view as will appear as the description proceeds, the invention resides in certain 20 novel features of construction, and in the combination and arrangement of parts as will be hereinafter more fully described and claimed.

In the drawing:

25 Figure 1 is a plan view of the tube embodying the features of my invention.

Figure 2 is a sectional view therethrough taken substantially on the line 2—2 of Figure 1.

30 Figure 3 is a detail section taken substantially on the line 3—3 of Figure 1.

Figure 4 is a plan view of another embodiment of the invention.

Figure 5 is a side elevation thereof, and

35 Figure 6 is a detail perspective view showing the connecting means between the tube sections.

Referring to the drawing in detail and particularly to Figures 1 to 3 inclusive it will 40 be seen that I utilize a continuous rubber tube and diametrically opposite portions 5 thereof have their walls cemented together as illustrated to advantage in Figure 3 so as to be flat like leaving the remaining diametri-

45 cally opposite disposed portions 6 inflatable and in these portions 6 are inflation valves 7.

Rubber bands 8 are disposed about the portions 6 and the valves 7 for protection purposes. With this device it will be seen that 50 portions 5 may be placed under the arms of

a person with air chamber portions 6 disposed one to the front and one to the rear thereby permitting any style of swimming by the person wearing the tube or life preserver.

55 In Figures 4 to 6 inclusive I have shown an embodiment wherein the tube is formed in two sections each having inflatable portions 6' and flat like end portions 5' formed in the same manner as portions 5.

60 These portions 5' are connectible together by means of hooks 9 and slots 10 as will be readily apparent from inspection of Figures 5 and 6. Thus these sections may be separated and put together enabling the device 65 to be more easily adjustable to the size of the person. Otherwise this modification is identical with the embodiment first described.

70 It is thought that the construction, utility and advantages of this invention will now be quite apparent to those skilled in this art without a more detailed description thereof.

75 The present embodiments of the invention have been disclosed in considerable detail merely for the purposes of exemplification 75 since in actual practice they attain the features of advantage enumerated as desirable in the statement of the invention and the above description.

80 It will be apparent that changes in the details of construction may be resorted to without departing from the spirit or scope of the invention as hereinafter claimed or sacrificing any of its advantages.

85 Having thus described my invention, what I claim as new is:

1. A device of the class described comprising a continuous tube, having oppositely disposed flap like portions and the remaining oppositely disposed portions inflatable, said 90 flap like portions having their walls extending together completely closing the ends of said inflatable portions, air valves in the inflatable portion.

2. A device of the class described, comprising a continuous tube having oppositely disposed flap like portions and the remaining oppositely disposed portions inflatable, said 95 oppositely disposed flap like portions having their walls extending together for completely 100

closing the ends of the inflatable portions, said flap like portions being formed in sections, two sections being attached to each inflatable portion, and means for detachably connecting the sections of the flap like portions together.

In testimony whereof I affix my signature.

WILLIAM B. PETZ.
